(57) **CLAIM**

The ornamental designs for a telescoping, bendable rod having measurement markings for measuring lengths, as shown and described.

DESCRIPTION

FIG. 1 is a perspective view of my new design in the closed configuration, showing a magnetic tip on the lower end and a clip on the upper end;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of my new design in the extended open configuration.

1 Claim, 7 Drawing Sheets

FIG. 2

FIG. 3

FIG. 4

FIG. 5

FIG. 6

FIG. 7

FIG. 8
